UNITED STATES PATENT OFFICE.

LILLIAN GLASER, OF DETROIT, MICHIGAN.

GAS-MANTLE.

1,335,831.

Specification of Letters Patent. Patented Apr. 6, 1920.

Application filed October 11, 1917. Serial No. 196,064.

To all whom it may concern:

Be it known that I, LILLIAN GLASER, a citizen of the United States of America, residing at Detroit, in the county of Wayne and State of Michigan, have invented certain new and useful Improvements in Gas-Mantles, of which the following is a specification, reference being had therein to the accompanying drawings.

10 In the preparation of self lighting incandescent mantles for burners and gas jets it is difficult to maintain the catalytic matter upon the mantle as it is not cohesive and is frequently shaken off while the mantle 15 is being transported, or if it is subject to vibration when in use.

This invention relates to a self lighting mantle in which the catalytic material is fused directly to the fabric of the mantle 20 in such manner as to withstand rough usage in transportation and in service and at the same time to distribute the heat effectively for igniting purposes.

The invention consists in the matters hereinafter set forth and more particularly 25 pointed out in the appended claims.

The drawing is a view in elevation of a mantle embodying features of the invention.

Spots 1 or buttons molded of equal parts 30 of platinum black and silicious material, such as finely powdered pumice stone of a quality that fuses slightly under the heat of a burning mantle, are applied in the form of a thick paste with a soft paraffin 35 carrier, to the mantle fabric, being connected by bands 2 of a similar material. Any gum soluble in acetone but not readily dissolved

in other solvents, such for example as gum sandarach, is employed to protect the mantle 40 for shipping purposes.

Under the effect of a current of gas the catalytic matter glows and under the heat of the burning mantle, a fusion takes place of the silicious material which binds the entire mass together and intimately unites 45 to the fabric of the mantle.

By this way a very durable and effective self-lighting mantle is obtained which may be used for gas jets, pilot flames or in other places where it is desirable to have self- 50 igniting burners.

Obviously, changes in the details of construction may be made without departing from the spirit of my invention and I do not care to limit myself to any particular 55 form or arrangement of parts.

What I claim is:—

1. A mantle or incandescent body for incandescent gas-lamps, in combination with an automatic gas igniter composed of equal 60 parts of platinum black and silicious material fused on the body of the mantle.

2. A mantle or incandescent body for incandescent gas-lamps, in combination with an automatic gas igniter consisting of pellets and bands composed of equal parts of 65 platinum black and silicious material fused on the body of the mantle.

In testimony whereof I affix my signature in the presence of two witnesses.

LILLIAN GLASER.
